ELECTRON DISCHARGE DEVICE

Adolph W. Schmidt, Norwood Park Township, Cook County, Ill., assignor to The Rauland Corporation, a corporation of Illinois

Filed Mar. 31, 1958, Ser. No. 725,315

4 Claims. (Cl. 313—65)

This invention relates to electron discharge devices such as X-ray image converters and more particularly to a novel method of increasing the output of a composite pick-up screen used in such image converters.

Most modern X-ray image converters consist of a substantially evacuated envelope containing a composite multiple layer pick-up screen, a fluorescent viewing screen remote from the pick-up screen upon which a reproduction of an original source image is projected, and an electron optical system intermediate the multiple layer pick-up screen and the fluorescent viewing screen for the purpose of accelerating and focusing an electron image on the fluorescent viewing screen, to produce thereon a light image of high intensity.

The composite multiple layer type pick-up screen usually consists of a phosphor layer, a barrier layer, and a photoemissive layer, all contiguous and applied to a relative thin radiation transparent light opaque supporting member. In operation, the phosphor layer is excited by impinging invisible radiation quanta which, in turn, generates an electron emission from the photoemissive surface and that surface generally constitutes the cathode member of the electron optical system.

It is important to develop the most efficient phosphor-photoemissive multiple layer pick-up screen possible, and a phosphor such as silver activated zinc sulphide suspended in a resinous vehicle is frequently used in combination with a cesiated-antimony photo-electric surface. To achieve an efficient multiple layer pick-up screen, it is vitally important that the efficiency of the phosphor-resin layer be as high as possible. Its efficiency is dependent on several factors, including the following: the amount of radiation quanta absorbed in such layer; the energy efficiency of the phosphor itself; and the forward reflection of the light quanta emitted in the direction of the support member. It has also been found important that the adherence of the multiple layer pick-up screen to its support member be as substantial as possible.

It is therefore an object of this invention to provide an improved multiple layer pick-up screen for X-ray image converters characterized by a high diffuse reflective surface.

It is also an object of this invention to provide a multiple layer pick-up screen for X-ray image converters having improved adherence to its support member.

It is a further object of this invention to provide a multiple layer pick-up screen for X-ray image converters having an improved support member which is transparent to incident radiation and possesses a non-specular surface.

In accordance with the invention, a multiple layer pick-up screen for an image converter comprises a layer containing a phosphor responsive to incident radiation of one type to emit a corresponding radiation of another type. The phosphor layer is applied to a support member which is transparent to incident radiation and has an etched surface to which the phosphor layer is affixed.

The features of the present invention which are believed to be novel are set forth with particularity in the

2

appended claims. The invention together with further objects and advantages thereof may best be understood, however, by reference to the following description taken in connection with the following drawing in which:

5 Fig. 1 is a cross-sectional side view of an X-ray image converter according to the invention;

Fig. 2 is an enlarged view of a section of the multiple layer pick-up screen embodied in the image converter of Fig. 1.

10 The image converter tube shown in the drawing comprises a substantially cylindrical glass envelope section 10 having an end portion in the form of a re-entrant press 11 and a substantially spherical glass envelope section 12 of a diameter approximately equal to that of envelope section 10. Envelope sections 10 and 12 are presealed around their entire perimeters to respective metal flanges 13a and 13b which in turn are sealed together by heliarc welding or the like. Suitably mounted within the spherical shaped end section 12 is a substantially spherical composite pick-up screen 14, the concave surface of which faces toward the re-entrant end of cylindrical envelope section 10. The re-entrant section 11 is closed by a flat glass plate 15 on the inside of which a suitable fluorescent viewing screen 15a of silver activated zinc cadmium sulphide or the like is provided. To the inside of re-entrant section 11 is attached a metal anode 16 to which is attached a substantially spherical shaped cap 17 provided with an axial circular aperture 18 to provide access for electrons originating at multiple layer pick-up screen 14

30 to fluorescent viewing screen 15a. Anode 16 completely encloses and is electrically connected to fluorescent viewing screen 15a. The convex face of anode cap 17 faces the concave surface of composite pick-up screen 14. Substantially the entire cylindrical portion of envelope 10 is 35 covered by electrode 19 in the form of a conductive wall coating which may be of copper or the like and is electrically connected to metal flange 13a. The construction details of the image converter tube as thus far described may be entirely conventional and will be familiar to persons skilled in the art.

In accordance with the invention the multiple layer pick-up screen 14 comprises a spherically shaped support member 14a to which is applied a phosphor-resin layer 14b. Contiguous to phosphor-resin layer 14b is applied a barrier layer 14c over which is applied a photoemissive layer 14d. Support member 14a is composed of an X-radiation transparent material such as aluminum of a thickness sufficient to rigidly support the multiple layers applied thereto. Phosphor-resin layer 14b consists of an X-ray sensitive phosphor such as silver activated zinc sulphide or the like embedded in a suitable organic silicon resin and applied to the spherical shaped aluminum supporting member 14a. Over this is applied a thin barrier layer 14c which may be of aluminum oxide or the like, of a thickness of approximately 100 angstroms. Applied to the surface of barrier layer 14c is photoemissive cathode layer 14d which may be of the conventional cesiated antimony composition.

When an X-ray image is directed toward the convex surface of the multiple layer pick-up screen 14, the image passes through aluminum support member 14a and excites phosphor-resin layer 14b to produce a visible image of the impinging X-radiation. This visible or light image passes through barrier layer 14c and excites photoemissive layer 14d which generally constitutes the cathode member of the focusing and accelerating lens system of the X-ray image converter. Photoemissive cathode 14d emits an electron image having a charge distribution corresponding to the incident light, hence the original X-ray image.

The focusing and accelerating electrode system, con-

sisting of photoemissive cathode 14d, high voltage anode 16, and electrically conductive focus electrode 19, when energized with proper electrical potentials, causes the image to be accelerated to and focused upon fluorescent viewing screen 15a.

It has been found that etching the surface of supporting member 14a substantially increases the reflectivity of the supporting member, which higher reflectivity results in greater over-all efficiency of the phosphor-resin light producing layer 14b. A sufficient etch is accomplished by immersing the supporting member in a ten percent solution of sodium hydroxide for 15 to 20 minutes at a temperature of approximately 50 degrees centigrade. In the event any problem is encountered in maintaining thickness control of the supporting member, it can be etched on the concave face only, by depositing a ten percent solution of sodium hydroxide within the concave surface of the supporting member for approximately the same length of time and at the same approximate temperature. Neither the time nor the temperature is critical, except insofar as the material thickness is affected, which should not be less than approximately 8 mils thickness to maintain sufficient rigidity. Various other methods exist for producing a non-specular surface and the above method is merely illustrative, not restrictive.

As previously stated, it is extremely important that the efficiency of phosphor-resin layer 14b be as high as possible and that such efficiency is in part a function of the light quanta emitted in the direction of the support member 14a. It stands to reason, therefore, that the higher the diffuse reflectivity produced in support member 14a the greater the over-all efficiency of the phosphor-resin light producing layer 14b.

Actual tests have indicated that phosphor-resin layer 14b applied to a highly polished support member 14a produces substantially less light quanta than it does when applied to etched support member 14a. The exact reason for this is unknown, but it is believed it is due to the higher numerical incident of possibility of reflected light quanta from an etched surface than that possible from the smooth surface. The improvement in brightness or light output is substantial from the phosphor-resin applied to the etched surface.

In addition to the previous gain, the adhesion of phosphor-resin layer 14b to etched aluminum support member 14a is substantially increased, contributing to a reduction in the number of reject units in producing such screens in production thereby effecting substantial economies in quantity production.

While a particular embodiment of the present invention

has been described, it is apparent that various changes and modifications may be made, and it is therefore contemplated in the appended claims to cover all such changes and modifications as fall within the true spirit and scope of the invention.

I claim:

1. A multiple layer pick-up screen for an image converter comprising: a layer containing a phosphor responsive to incident radiation of one type to emit a corresponding radiation of another type; a support member for said layer which is transparent to said incident radiation and has an etched surface to which said layer is affixed; and a photoemissive layer responsive to said other type radiation superimposed on said phosphor layer on the face thereof opposite said support member.

2. A multiple layer pick-up screen for an image converter comprising: a layer containing a phosphor suspended in a resinous vehicle and responsive to incident radiation of one type to emit a corresponding radiation of another type; a support member for said layer which is transparent to said incident radiation and has an etched surface to which said layer is affixed; and a photoemissive layer responsive to said other type radiation superimposed on said phosphor layer on the face thereof opposite said support member.

3. A multiple layer pick-up screen for an X-ray image converter comprising: a phosphor layer suspended in a resinous vehicle and responsive to X-ray radiation; a support member for said phosphor layer which is transparent to X-ray radiation and has a non-specular surface to which said X-ray sensitive phosphor layer is affixed; and a photoemissive layer responsive to radiation from said phosphor layer superimposed on said phosphor layer on the face thereof opposite said support member.

4. A multiple layer pick-up screen for an X-ray image converter comprising: a phosphor layer responsive to X-ray radiation; a support member for said phosphor layer which is transparent to X-ray radiation and has an etched surface to which said X-ray sensitive phosphor layer is affixed; and a photoemissive layer responsive to radiation from said phosphor layer superimposed on said phosphor layer on the face thereof opposite said support member.
